JOHN H. STEWART, OF JAMAICA, NEW YORK, ASSIGNOR TO THE COBURN TROLLEY TRACK M'FG COMPANY, OF HOLYOKE, MASSACHUSETTS, A CORPORATION OF MASSACHUSETTS.

SELF-CLOSING PENDULUM-HANGER FOR DOORS.

1,275,175.

Specification of Letters Patent.

Patented Aug. 6, 1918.

Application filed December 5, 1917. Serial No. 205,586.

To all whom it may concern:

Be it known that I, JOHN H. STEWART, a subject of the King of Great Britain, and a resident of Jamaica, borough of Queens, in the county of Queens and State of New York, have invented certain new and useful Improvements in Self-Closing Pendulum-Hangers for Doors, of which the following is a full, clear, and exact description.

10 This invention relates to improvements in sliding doors. In the illustration accompanying this application it is shown as being applied to elevator wells, but it is of course understood that its application is not restricted to any particular use, since it may readily be adapted to other uses as desired, as for example, barn or car doors. It relates, in general, to the type of doors shown and described in Letters Patent of the United States granted to me on December 12, 1916, #1,208,690, for self closing pendulum hanger for doors, and in my pending application Serial #177,300, filed June 27, 1917, known as pendulum hangers for doors. 20 The present invention differs from these referred to in having the door closing weight located above the door in a recess or opening immediately above that part of the door frame or case at the upper end of the doors. 25 The invention, broadly considered, comprises one or more sliding doors to which is pivotally connected a swinging link, the upper end of the link being pivotally connected to a fixed support, the link having a part coöperating with a weight for automatically closing the door after the same has been opened. Devices are also provided for causing the weight to close a second door as the first one is operated.

30 Referring to the drawings:

Figure 1 shows the position of the door after being opened, with the weight elevated for returning the door to its closed position.

Fig. 2 shows the door in closed position.

45 In this view two movable doors are shown with connecting devices for operating one from the other.

50 Fig. 3 is a vertical sectional view on the line 3—3 of Fig. 1 showing the arrangement of the operative parts and

55 Fig. 4 is a horizontal sectional view on the line 4—4 of Fig. 2 showing two movable

door sections arranged for sliding or passing by each other and a fixed door section.

Fig. 5 is a modification of the weight 55 operating mechanism.

Referring to the drawings in detail:

1 and 2 designate the upright door casing member, 3 the horizontal member of the door casing located immediately above the upper 60 edge of the doors; 4 is a beam or girder which may be of channel iron and to which the door supporting pendulum is attached. 5 is a pendulum bar which is pivotally attached to the beam 4 by any suitable means, 65 as a plate 6 and pin 7, the plate having a slot, if desired, for the purposes of adjustment. The pendulum bar 5 is pivotally connected to the door 8 by means of the crank 9 and pin 10, the crank being also pivotally 70 connected to the door 8 by means of the plate 11, which, as shown, is set into one of the lower panels and secured thereto by means of bolts 12 and 13. The pendulum bar 5 is further connected to the door 8 by means of 75 the slot 14 in the pendulum and the pin 15, which is carried by the plate 11. It is to be understood that the connection of the crank 9 to the door, and the pin 15, are in a line passing through the center of 80 gravity of the door. The bar 5 has attached thereto the curved arm, or extension 16, on which the roller 17 rests, which is rotatably attached to the weight 18. This weight is placed on the outer end of the rod 19, which 85 is pivotally connected to the building as indicated at 20. The effect of this weight, which is supported on the arm 16, is to normally retain the door 8 in a closed position as shown in Fig. 2. Connected to the bar 90 5 at a point substantially midway between the pivotal points 7 and 15, is a bar or strap iron 21 having an inwardly extending end 22 which, as shown in Fig. 4, is attached to the right hand edge of the sliding door 95 23, which is slidably supported by means of a second pendulum or bar 24, which is also connected to the plate 6 by means of the same pivotal pin 7, (see Fig. 3). The lower end of the bar 24 is attached to the door 100 23 by means of the crank 25 and pins 26 and 27 and the slot and pin connection 28 and 29. The piece 3 is slotted, as shown in Fig. 3, at 30 to permit the pendulum 24 to

pass loosely therethrough. The door section 31 is a fixed one. When the other two door sections are moved toward the right hand they will occupy a position at the side of 5 and in front of the door section 31.

Instead of the arm 16 being used, a bar 32, shown in Fig. 5, may be used. This bar is connected to the pendulum bar 5. Its outer end has attached thereto a weight 33 10 by means of the flexible connection 34.

The operation of the door hanger may be described as follows: As already stated, the action of the weight 18 is to normally retain the doors in a closed position. Should the 15 operator move the doors 8 and 23 to the open position (See Fig. 1) by grasping the latch 35, they will be moved from the position shown in Fig. 4 to that shown in Fig. 3. On account of the doors 8 and 23, being 20 hung, or supported, at their centers of gravity, they will be operated with very much less effort by the operator and have a tendency to remain in a vertical position. Their upper edges will be free from contact with 25 the beam 3. The weight of the doors is supported by means of suitable rollers located in the lower part of the doors, as shown at 36. The slot and pin construction 14, 15, 28 and 29 will readily permit the pendulum 30 bars 5 and 24 to have free and unrestricted movements during the opening and closing operations. After the doors 8 and 23 are opened and the operator releases his grasp on the latch 35, they will close automatically 35 by reason of the weight 18, and roller 17 acting on the arm 16, or, weight 33 on the arm 32. It should be stated that the door 23 will be moved by the bar 21 to its open or closed position when the door 8 is operated. 40 This door 23 will have a rate of movement one half that of the door 8 by reason of the bar 21 being connected at a point midway between the pivots 7 and 15.

From this description it will be seen that 45 the weight 18 is located in recesses that are separate from the door and in a position that will not endanger the operator. Also the crank and pin connection 9 and 10, 26 and 27, is located in a recess of the door 50 itself. It will also be observed that the device is very simple in construction, having few parts that are constructed from comparatively inexpensive material.

What I claim is:

55 1. A sliding door operating device comprising, in combination with the door to be operated, of a pendulum bar having pivotal connections with a fixed support above the door-way, its lower end having a crank and pin connection with the door and also in addition a slot and pin connection with the door in the same vertical line as the crank and pin connection, and devices including a weight operating on an arm attached to 60 the pendulum bar for returning the door to

its normally closed position, said means comprising an arm on the pendulum bar and a movable weight engaging the arm for the purpose set forth. 70

2. A sliding door construction, comprising, in combination, door sections, of a swinging bar that is pivotally secured to a fixed support adjacent the door-way and to the door section to be moved, a second door-section, a second swinging bar pivoted to the 75 fixed support at the same point as the first mentioned swinging bar and connected to the second door section, a bar connected to the first-mentioned swinging bar and to the second door section for causing the two door 80 sections to move together, but at different rates of motion, and a weight, the action of which is common to the two door sections and swinging bars for returning the doors to their normally closed position. 85

3. A sliding door construction comprising, in combination, a pendulum bar having a pivotal connection with a fixed support at one end and a door section connected to the said bar at its other end, the latter connection including a crank arm, a slot and pin connection of the pendulum bar with the door section, said bar having an inclined position when the door-section is normally closed, a weight having an independent pivotal connection with the fixed support, and inter-engaging means between the weight and the pendulum bar for returning the door section to and maintaining the same in its normally closed position. 90

4. A door operating device comprising, in combination with the door to be operated, of a pendulum bar having pivotal connection with a fixed support above the doorway, its lower end having a crank and pin connection with the door at a point which is located in a line passing through the center of gravity of the door and a slot and pin connection with the door, also located in said line, and devices for returning the door to its normally closed position, said means comprising an arm on the pendulum bar and a movable weight engaging the arm for the purpose set forth. 100

5. A sliding door construction comprising two door sections, devices for causing said sections to move together but at different rates or speeds, and comprising two pendulum bars pivotally hung from the same fixed point, each bar having a crank and pin and a slot and pin connection with a door section, and a connection from one of said bars which connects one door section to the other door section. 115

6. A sliding door construction, comprising, in combination, door sections, pendulum operating bars for said sections, means for moving one section from the other, means for returning the door sections to their initial positions comprising a rod having a 120 125 130

5 pivotal connection with a fixed support, a weight on the rod, an arm on one of the pendulums for receiving the weight to cause the door sections to return to their initial position.

7. A sliding door construction comprising, in combination, a door section, a one-piece pendulum directly connected to the door section for operating the same, means arranged adjacent the pivotal point of the pendulum for returning the door section to its first position after being removed therefrom and comprising an arm on the pendulum and a weight movable on the arm.

15 8. A sliding door construction, comprising,

ing, in combination, a door section, a pendulum for operating said section during its opening and closing movements, and connected to a fixed support at a point substantially in line with the center of gravity of the door section, and passing across the side of the door, a weight device for automatically returning the door section to its initial position comprising an arm on the operating pendulum, a bar having a pivotal connection with the fixed support and on which latter bar a weight is located, and a roller carried by the weight for engaging the arm on the pendulum for the purpose described.

JOHN H. STEWART.
